RETAINER REMOVER

Stewart G. Hallenborg, Tenafly, N. J.

Application March 28, 1946, Serial No. 657,868

1. Claim. (Cl. 29—283)

1.

This invention relates to a tool for removing a fastener by means of which the handles for doors and windows of automobiles are secured to the shafts carrying the same. At the present time such handles are secured to the shafts by a spring steel wire retainer and it has been customary to remove them by use of a device similar to a crochet hook and another sharp implement resembling a nice pick. It is very difficult to remove the fasteners with such implements and it often happens that when they are removed they will fly off and become lost or injure a mechanic by striking his eye.

Therefore one object of the invention is to provide an instrument by means of which the wire fasteners may be very easily removed and without becoming lost or injuring a workman by striking his eye.

Another object of the invention is to provide a tool so formed that it may be slipped into engagement with a handle and then be actuated to remove the fastener, the fastener when removed from the door handle remaining in the removing tool so that it does not fly off and become lost.

Another object of the invention is to provide a tool which may be used for removing fasteners from handles of different sizes.

Another object of the invention is to provide a tool so formed that it may be thrust into place between a handle and a confronting surface of a door and having straddling engagement with a shaft-engaging portion of the handle so that a clip holding the handle to the shaft may be gripped and withdrawn to release the handle from the shaft.

Another object of the invention is to provide a tool so formed that after it has been thrust into place it is merely necessary to move a handle of the tool and thereby turn a shaft which is geared to a plunger and moves the plunger longitudinally to draw a plate carrying jaws upwardly and cause the jaws to firmly grip the clip and dislodge it from the door handle.

Another object of the invention is to provide a tool having an insert so mounted that it may be removed and another insert carrying jaws of a different size substituted for use.

Another object of the invention is to provide a tool wherein the insert is releasably held in place by a member which also serves as means holding the tool in engagement with a handle from which its securing clip is to be removed.

Another object of the invention is to provide a tool having the clip-engaging jaws so mounted

2.

that as a plate carrying the jaws is slid upwardly the jaws will be automatically moved to a gripping position where they will be held until the plate is shifted downwardly for return of the jaws to their normal position. It will thus be seen that the clip cannot be accidentally released and fly off as it is withdrawn from a door handle and become lost.

Another object of the invention is to provide a tool of this character which is simple in construction and very efficient in operation.

The invention is illustrated in the accompanying drawings wherein:

Figure 1 is a front view of the improved clip removing tool.

Figure 2 is a sectional view taken longitudinally of the tool along line 2—2 of Figure 1.

Figure 3 is a bottom view of the tool.

Figure 4 is a fragmentary view partially in section and partially in elevation showing the jaws in their normal position.

Figure 5 is a view looking at the rear face of the lower portion of the tool.

Figure 6 is a view similar to Figure 4 showing the tool in position to remove a clip from a door handle.

Figure 7 is a sectional view taken along line 7—7 of Figure 6.

Figure 8 is a view similar to Figure 6 showing the jaws in gripping engagement with the clip.

Figure 9 is a view showing the clip withdrawn from the door handle.

Figure 10 is a transverse sectional view taken along line 10—10 of Figure 9.

Figure 11 is a view showing the lower portion of the tool in vertical section and the door handle in side elevation.

Figure 12 is a view showing clip-engaging jaws of a modified formation.

Figure 13 is a rear view of the jaw carrying casing shown in Figure 12.

Figure 14 is a front view of the jaw carrying casing shown in Figure 12.

Figure 15 is a view taken along line 15—15 of Figure 12 and showing the tool applied to a door handle.

Figure 16 is a view similar to Figure 14 showing another modified form of jaws.

Figure 17 is a view similar to Figure 12 showing the jaws of Figure 16.

Figure 18 is a front view of a modified form of tool.

Figure 19 is a sectional view taken along line 19—19 of Figure 18 and showing the tool applied to a door handle.

55

Figure 20 is a transverse sectional view taken along line 20—20 of Figure 19.

Figure 21 is a fragmentary view showing the lower portion of the modified form of tool.

Figure 22 is a side view of the lower portion of the modified form of tool.

Figure 23 is a side view showing the modified form of tool opened.

Figure 24 is a front view of the clamp of the modified form of tool.

This improved tool is employed for removing a clip 1 by means of which a handle 2 is held upon a shaft 3. This handle may be the handle by means of which a door of an automobile is opened and closed or may be the handle by means of which the glass for a door or window of an automobile is shifted to open and closed positions. The shank 4 of the handle is formed with a socket 5 into which the shaft fits and side portions of the shank are formed with openings 6 which register with a groove 7 formed circumferentially of the shaft, and when the clip 1 is applied its arms pass through the side openings 6 and enter the groove 7. Therefore the handle will be firmly held to the shaft and when the handle is turned the shaft will be rotated and the door latch released or the glass moved to opened or closed position accordingly to the direction in which the shaft is turned. Interengaging teeth 8 and 9 of the shaft and the handle causes the shaft to turn with the handle. When the handle is in place upon the shaft it is quite close to the door or side wall of the automobile and difficulty has been experienced in withdrawing the clip when the handle is to be removed. At the present time it is customary for workman at a service station to use tools resembling a crochet hook and an ice pick for removing the clips but such tools are not satisfactory as the clips, when dislodged, are liable to fly off and become lost or strike the workman's eye and cause injury to his eye.

The improved tool constituting the subject matter of this invention may be used without danger of injury to the workman or loss of the clip. This tool has a frame 10 having arms 11 at its sides formed with inwardly projecting fingers 12 at their lower ends. A plate of thin metal 12 which is secured by a suitable number of screws 13 forms a rear wall for a pocket 14 defined by the inverted U-shaped frame and this rear wall 12 is formed midway the width of its lower end with a recess 15 from opposite sides of which project ends of the fingers 11. A hollow handle 16 of tubular formation projects upwardly from the frame 10 to which its lower portion is welded in straddling relation thereto, and at its upper end the handle is closed by a plug 17 held in place by screws 18. A rack bar 19 is slidable longitudinally through the rear arm or fork 20 of the handle and at its upper end the rack bar is formed with a head 21 which is of such diameter that it may move through the handle. A spring 22 which is held in the handle by the plug 17 bears against the head 21 and yieldably holds the rack bar in the lowered position with its lower end abutting the stop 23 at the lower end of the rear fork 20. Bars 25 project forwardly from opposite sides of the handle just above the frame 10 and form a housing 26 closed by a front wall or plate 27. A shaft 28 is rotatably mounted transversely through the housing 26 and is held against longitudinal displacement by a collar 29 which is held to the shaft by a screw 30. At its other end the shaft is formed

with a head 31 bored to form a socket 32 and into this socket is screwed the threaded lower end of a lever 33. When this lever is grasped and swung downwardly the shaft will be turned and since this shaft carries a gear 34 meshing with the rack bar 19, the rack bar will be shifted upwardly and the spring 22 compressed. When the lever is released the spring expands and returns the rack bar in its original position. The lower end of the rack bar is exposed in the upper portion of the pocket 14 and is formed with a lug 34' which engages and operates clip engaging means 35 in the pocket 14.

The clip-engaging means 35 has a casing 36 formed of front and rear plates 36 and 37 held in spaced relation to each other by side strips 38 which are secured between side edge portions of the plates by screws 39. Recesses 40 and 41 are formed in lower portions of the plates or walls 36 and 37 and the plate 37 has its upper portion formed with a recess 42 leading from its upper end. Arms 43 extend from upper ends of the strips 38 with their ends terminating at opposite sides of recess 42 and at their lower ends 25 the strips 38 are provided with extensions or arms 44 having end portions of reduced thickness to provide lips 45 having their lower ends bevelled to sharp edges. At opposite sides of the lower end of the recess 41 the plate 37 is bevelled as shown at 46 to form sharp edges which cooperate with the bevelled surfaces of the lips 45 and form guides for directing the clip-engaging member into position between the handle 2 and the surface of the door. Upper edges 20 47 of the arms 44 extend at an incline and are flush with lower edges of recesses 48 formed in the side strips 38 near lower ends thereof.

Within the casing 35 is a block 49 which is slidable vertically or longitudinally of the casing and has a shank 50 which is disposed between ends of the arms 43 and is formed with an opening 51 into which fits the lug 34 of the rack bar 19. When the rack bar is shifted upwardly the block 49 will be moved with it to a raised position 45 and when the spring 22 shifts the rack bar downwardly the block will be returned to its normal position. Jaws 52 fit within the casing 35 under the block 49 and these jaws have upstanding shanks or stems 53 terminating in circular head 54 which fit into circular sockets 55 formed in the block 49 and mount the jaws for tilting movement towards and away from the recesses or seats 48. When the device is applied to a handle 2 in straddling relation to the shank 4 of the handle and the lever 33 moved to shift the rack bar upwardly the jaws will be shifted towards each other by cam action between the tapered lugs 56 of the jaws and the sloping upper edges of the recesses 48 and the teeth 57 of the jaws 60 brought into gripping engagement with the clip from opposite sides thereof as shown in Figure 8. Continued upward movement of the block and the jaws will cause the jaws to move upwardly between the side strips 38 and withdraw the clip 65 from the handle and the shaft and the handle will be released from the shaft for removal therefrom. The doors of automobiles do not all have the same size handles and some have clips of different shapes. Therefore there have been shown in Figures 12 through 17 jaws having clip-engaging inner side edges of different shape from the jaws shown in Figures 4 through 9. A specific description of the jaws shown in Figures 12 through 17 is not necessary as they differ from 70 the jaws of Figures 4 through 9 only in the shape

of their inner side edges. When the lever 33 is released and the spring 22 returns the rack bar and the block to the initial or lowered position the jaws move downwardly with the block and since the jaws are urged apart by a plunger 33 forced downwardly by a spring 59 the jaws will be moved apart and into the recesses 48. Therefore the clip will be released and will drop into the hand of a workman held under the tool. If it is found that the jaws of a clip engaging member 35 do not fit the clip and handle to be removed it is merely necessary to remove the casing 35 and insert one having jaws of the proper size and shape. When the casing is fitted into the pocket 14 and the lug 34 engaged in the opening 51, the casing must be prevented from slipping out of the pocket during use of the tool. In order to do so there has been provided a clamp 60 carried by short shafts 61 which are rotatably mounted through bearings 62 at opposite sides of the frame 10. Inner ends of the shafts are formed with heads 63 constituting cams and when the clamp is in its raised position the casing 35 may be slipped into the pocket 14 with its side edge portions moving under the flat faces of the cams. After the casing is in place the clamp is swung downwardly and the cams move into gripping engagement with the casing. When the tool is to be applied to a door handle the clamp is swung upwardly and the tool slid downwardly into straddling engagement with the shank of the door handle. The clamp is then swung downwardly to firmly hold the casing in the frame of the tool and the door handle 2 engages in the notch 64 formed in the bridge of the clamp so that the tool will be held close against the door and prevented from shifting upwardly by wedging action of the handle 2 in the notch 64. When the clamp 61 is swung upwardly out of engagement with the door handle the tool may be easily moved upwardly out of engagement with the door handle and carry the clip with it.

In Figures 18 through 24 there has been shown a modified form of clip removing tool. In this embodiment of the invention the frame 64 has side bars 65 corresponding to the side bars or arms of the frame 10 and at the upper ends of the side bars there is formed a handle 68 which is of inverted U-shape and takes the place of the rigid handle 10. The casing 69, carrying the sliding block 70 and the jaws 71 which are pivoted to the block, fits into the frame 64 between the side bars 65 of the frame and since the action of the jaws during vertical movement of the block is the same as previously described it is not necessary to specifically describe the same. A space is provided between ends of the inwardly projecting fingers at upper ends of the side bars of the casing for allowing outward movement of the shank of the block 70 as the block moves upwardly and this space registers with the passage 72 of the main frame. A rack 73 is formed longitudinally of the block and its shank and with this rack meshes a gear 74 carried by a shaft 75. The shaft 75 is rotatably mounted through a housing 76 carried by and projecting forwardly from a plate 77 which is provided at its upper ends with bearings 66 through which pins 67 are passed to pivotally mount the plate 77 on the frame 64 and the plate rests against the outer face of the casing 69 and side bars 65 of the main frame and is firmly secured by hooks 78 extending from ends

of the arms of the clamp 79. This clamp has its arms pivotally mounted by pins 80 which pass through bearings 81 at opposite side edges of the plate 77 and when the clamp is swung downwardly the hooks 78 engage the pins or lugs 82 at sides of the main frame and firmly secure the plate to the main frame. Springs 83 surround the shaft 75 within the housing 76 and when the shaft is rotated to shift the block upwardly by applying downward pressure to the handle 68 of the shaft the springs which are anchored to the shaft and end walls of the housing will be tightened and serve to impart reverse rotation to the shaft and lower the block and the jaw when the handle is released. In both embodiments of the invention illustrated the jaws will grip the clip and withdraw it from the door handle when the block is shifted upwardly and when the clamp is swung downwardly to its lowered position it serves to firmly hold the clip-engaging means in place within the main frame as well as serving to engage the door handle and holding the tool anchored to the door handle during removal of the clip.

Having thus described the invention, what is claimed is:

In a tool for removing a handle-securing clip, a frame embodying a pair of spaced arms, a clip-engaging means operatively connected to said frame, said clip-engaging means comprising a pair of spaced side strips secured to said arms, there being an opposed recess in the inner face of each of said side strips, said recesses being arranged adjacent the lower ends of said side strips and having a substantially V-shape, the recesses extending inwardly from the inner longitudinal edges of said side strips, said recesses being arranged in alignment with each other, a plate arranged on each side of said frame and secured to said side strips, a block slidably positioned between said side strips, a shank projecting from one end of said block, there being a pair of spaced circular sockets in the other end of said block, a circular head seated in each of said sockets, a stem secured to each of said heads, and a jaw secured to each of said stems, said jaws being mounted for movement toward and away from each other, each of said jaws being provided with a V-shaped lug at its lower end for cooperating with said recess to produce movement of said jaws toward and away from each other, means operatively connected to said jaws for normally urging the latter apart, and V-shaped teeth on the inner faces of said jaws for gripping said clips therebetween.

STEWART G. HALLENBORG.
